UNITED STATES PATENT OFFICE.

CHARLOTTE M. ROCHTE, OF CHICAGO, ILLINOIS.

CHILD'S WAIST.

1,115,577.

Specification of Letters Patent.

Patented Nov. 3, 1914.

Application filed April 9, 1914. Serial No. 830,652.

To all whom it may concern:

Be it known that I, CHARLOTTE M. ROCHTE, a citizen of the United States, and resident of Chicago, county of Cook, and State of Illinois, have invented certain new and useful Improvements in Children's Waists, of which the following is a specification, and which are illustrated in the accompanying drawings, forming a part thereof.

The invention relates to garments and more particularly to waists such as are worn by children and serve as a support for the petticoats, drawers and garters.

The object of the invention is to provide a garment of the type described which will respond to the movements of the body without transmitting strains to the lower garments and which shall be adjustable in size to support garments of different lengths at a uniform height.

The invention is exemplified in the device which is hereinafter described and which is illustrated in the accompanying drawings, wherein,

Figure 1 is a perspective view illustrating a waist embodying the features of improvement provided by the invention; and Fig. 2 is a detail section view taken on the line 2—2 of Fig. 1.

In carrying out the invention, a bodice 10, and a belt 11 are provided. The bodice 10 is preferably constructed to cover the shoulders and chest of the wearer and has the usual arm holes, as 12 and 13. The belt 11 encircles the waist below the bodice 10, and is spaced apart therefrom. Both the bodice 10 and belt 11 are open at one side, preferably the back, and have buttons, as 14 and 15, for closing this side of the garment when it has been applied to the wearer. The belt 11 is also supplied with the usual buttons as at 16, 17 and 18 at the front and at the two sides for the attachment of the drawers and petticoats, and loops 19, 20 for attachment of the garters.

An adjustable and flexible connection of the belt 11 with the bodice 10, is provided by means of a strap 21. This strap is desirably made from elastic material and will preferably be provided in a single continuous length. As shown, its two ends are connected to the belt 11 at the back of the garment adjacent the two ends of the belt. For this purpose buckles 22 and 23 are pro-

vided. Each of these buckles is connected to the corresponding end of the belt 11 to project obliquely upwardly therefrom, as by means of a loop 24. From the buckles 22, 23, the strap 21 extends alternately through loops, as 25, 26, 27 and 28, attached to the bodice 10 and loops, as 29, 30 and 31 attached to the belt 11. Each of the loops 25, 26, 27, 28, 29, 30 and 31 conveniently takes the form of a flattened metal ring and is secured in position upon the corresponding part of the garment by means of a tape, as 32. To permit a free sliding movement of the strap 21 through all of these loops, a tubular piece of metal forming a roller, as 33, is applied to that side of each loop with which the strap is engaged. If desired, the bodice 10 may be reinforced by means of tapes, as 34 and 35 which extend between the points of connection therewith of the loops 25, 26 and 27, 28 respectively, and over the corresponding shoulder.

The construction provides for a relative movement between the belt 11 and bodice 10 at either side or at the front or back, accompanying the various movements of the body. This insures comfort to the wearer and relieves the strains which usually come upon the buttons and loops by which the drawers and garters are supported. Furthermore, the bodice 10 is of such a form as to insure its remaining in position upon the wearer, those parts of the same which extend over the shoulders being held in position in the same manner as pertains to waists which are formed in a single piece. Adjustment of the length of the strap 21 between the buckles 22 and 23 also serves to raise or lower the position of the belt 11 in accordance with the length of the garments to be secured thereto. This last mentioned feature is of importance in permitting a child to wear drawers and petticoats which it would otherwise have outgrown.

I claim as my invention,

1. In a waist, in combination, a bodice adapted to cover the shoulders of the wearer and having arm holes, a belt adapted to encircle the body below the said bodice and constructed for the attachment of nether garments thereto, loops fixed upon the adjacent edges of said parts and a strap sliding in the said loops, said strap engaging the loops upon the two members in alternation.

2. In a waist in combination, a bodice adapted to cover the shoulders of the wearer

and having arm holes, a belt adapted to encircle the body below the said bodice and constructed for the attachment of nether garments thereto, loops fixed upon the adjacent edges of said parts, an elastic strap sliding in the said loops, said strap engaging the loops upon the two members in alternation.

3. In a waist, in combination, a bodice 10 and a belt constructed for the attachment of nether garments thereto, the said bodice being adapted to extend over the shoulders and about the body of the wearer below the arms and the belt being adapted to extend 15 about the body below the bodice and one of said members being openable, and a strap having its two ends fixed to the openable one of said first mentioned members adjacent to and at opposite sides of the point of

opening, the intermediate part of said strap 20 being slidably connected to the two first mentioned members in alternation.

4. In a waist, in combination, a bodice adapted to cover the shoulders of the wearer and having arm holes, an openable belt 25 adapted to encircle the body below the said bodice and constructed for the attachment of nether garments thereto, loops fixed upon the adjacent edges of said parts, and a strap sliding in the said loops and having its two 30 ends adjustably fixed to the belt adjacent to and at its opposite sides of the point of opening, said strap engaging the loops upon the two members in alternation.

CHARLOTTE M. ROCHE.
